(57) **CLAIM**

The ornamental design for a cover for tracking device or the like, as shown and described.

DESCRIPTION

FIG. 1 is a front, top, and left side perspective view of a cover for tracking device or the like, showing my design; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, top, and left side perspective view thereof; FIG. 9 is a cross-sectional view taken in the direction of line 9-9 shown in FIG. 2; and,

FIG. 10 is a front, top, and left side perspective view thereof in use.

The long dash short dash broken lines and arrows shown in FIG. 2 are used to identify the cross-sectional view and form no part of the claimed design. The evenly spaced broken lines shown in FIGS. 1, 2, 4-8, and 10 depict portions of the cover for tracking device or the like or environment and form no part of the claimed design.
